UNITED STATES PATENT OFFICE.

JOHN F. BEANS, OF CANTON, AND ALONZO J. MERCIER, OF MASSILLON, OHIO, ASSIGNEES TO THE BEANS SPRING COMPANY, OF MASSILLON, OHIO, A CORPORATION OF OHIO.

MACHINE FOR BENDING BUMPER BRACKETS.

Application filed November 17, 1922. Serial No. 601,592.

To all whom it may concern:

Be it known that we, JOHN F. BEANS and ALONZO J. MERCIER, both citizens of the United States, residing at Canton, Stark County, Ohio, and Massillon, Stark County, Ohio, respectively, have invented a new and useful Machine for Bending Bumper Brackets, of which the following is a specification.

- 10 This invention relates to a bending machine and more particularly to a device for bending a bracket especially designed for supporting an automobile bumper upon the automobile.
- 15 The objects of the invention are to provide a machine of this character in which a bracket may be easily and quickly formed, in two continuous operations, from a straight bar of spring steel or the like.
- 20 The above and other objects may be attained by providing a bending die around which the bar of steel is bent by a roller upon a swinging arm, a removable block being provided for engagement with the
- 25 partially completed product, a second roller upon a swinging arm being provided for bending the end portion of the bracket back upon the removable block to complete the bracket.
- 30 A practical embodiment of the invention thus set forth in general terms is illustrated in the accompanying drawings, in which—
Figure 1 is a plan view of the machine showing a bar in the initial position;
- 35 Fig. 2, a similar view showing the first bending operation of the bar;
Fig. 3, a similar view showing the second bending operation;
- 40 Fig. 4, an edge elevation of the table and bending die;
Fig. 5, a side view of one of the swinging arms and rollers; and
- 45 Fig. 6, a perspective view of one of the finished brackets.
- 50 Similar numerals of reference indicate corresponding parts throughout the drawings.
- 55 The machine includes a table 1 upon which is fixed a block 2 having the straight edge 3, and the curved edge 4 continuous therewith and terminating at the cut-out portion 5. One or more pins 6 are spaced from the straight edge 3 of the block to accommodate brackets of different sizes.
- 60 The blank A from which each bracket is

formed, comprises a straight bar of steel, one end of which has been bent into the hook 7 which is received upon the proper pin 6, the bar being placed against the straight edge 3 and extending outward beyond the block, as shown in Fig. 1.

The swinging arm 8 is provided with a downturned journal portion 9 which is then mounted in a bearing opening 10 formed in the block. The arm 8 has an enlarged portion 11 intermediate its extremities provided with an elongated slot 12 in which the squared portion 13 of a journal 14 is arranged to be adjusted as by the nut 15 upon the threaded end 16 thereof, said journal having a head 17 to prevent displacement of the roller 18 which is journaled thereon.

This arm is placed in the position shown in full lines in Fig. 1 and then swung around upon its pivot, the roller carrying the free end of the bar around the curved edge 4 of the block, assuming first the position shown at B in Fig. 1, and finally the position shown in Fig. 2, the free end of the bar A being extended past the cut-out portion 5 of the block.

The arm 8 is then removed and an arm 19 similar to the arm 8 having a roller 20 mounted closer to the pivotal point, is then brought into use, the journal portion of said arm being inserted into a bearing opening 21 in the table, the arm and roller first assuming the positions shown at C in dot and dash lines, the roller engaging the free end portion of the bar indicated at D in Fig. 3.

A removable bending block 21' is then inserted, as shown in Fig. 3, the curved edge 22 thereof engaging the curved portion of the bar, the end of said removable block engaging the journal portion 24 of the arm 19.

The arm 19 is then swung downward bending the free end of the bar to the position shown at E in Fig. 3 and continuing around into the position shown in full lines in said figure, forming the finished bracket as shown in Fig. 6, having the hooked upper end 7, the depending straight portion 25, the lower curved portion 26 and the downturned end 27.

The openings 28 may be punched in the blank before the same is placed in the bending machine, these openings forming no

part of the present invention, but being necessary in the finished bracket in order to connect the bumper, which is shown in a co-pending application.

5 It will thus be seen that with two easy and simple operations which are readily accomplished, the blank bar, after being properly heated, may be quickly and easily formed around the stationary block and 10 a removable block by means of the two pivoted arms, the rollers upon which press the bar around the bending blocks as above described.

We claim:—

15 1. A bending machine including a table, a fixed bending block thereon having a straight edge terminating in a curved edge, a swinging arm arranged to be pivotally connected to the block and provided with 20 a roller for bending the bar around the curved edge of the block, the table having a bearing aperture at the extremity of said curved edge of the block, a detachable arm having a journal portion adapted to be engaged in said bearing aperture, a removable block adapted to bear 25

journal portion, and a roller upon said detachable arm for bending the free extremity of the bar back upon the removable block.

2. A bending machine for bending a bar 30 provided with a hooked end and comprising a table, a fixed bending block thereon having a straight edge terminating in a curved edge, a pin in the table near the end of the straight portion of the block 35 for engagement with the hooked end of the bar, a swinging arm arranged to be pivotally connected to the block and provided with a roller for bending the bar around the curved edge of the block, the 40 table having a bearing aperture at the extremity of the curved portion of the block, a detachable arm having a journal portion adapted to be engaged in said bearing aperture, a removable block adapted to bear 45 against said journal portion, and a roller upon said detachable arm for bending the free extremity of the bar back upon the removable block.

JOHN F. BEANS.

ALONZO J. MERCIER.
